DESIGN FOR A FLASHLIGHT BASE CAP

Emerson H. Tompkins, Waterbury, Conn., assignor to Scovill Manufacturing Company, Waterbury, Conn., a corporation of Connecticut

Application February 28, 1936, Serial No. 61,411

Term of patent 14 years

To all whom it may concern:

Be it known that I, Emerson H. Tompkins, a citizen of the United States and residing at Waterbury, in the county of New Haven and State of Connecticut, have invented a new, original, and ornamental Design for Flashlight Base Caps, of which the following is a specification, reference being had to the accompanying drawing, forming part thereof.

Fig. 1 is a front view of the flashlight base cap, showing my new design.

Fig. 2 is a side view of the same.

Fig. 3 is a bottom view of the same.

I claim:

The ornamental design for a flashlight base cap as shown.

In testimony whereof, I have affixed my signature to this specification.

EMERSON H. TOMPKINS.
